US0D1000459S

(12) **United States Design Patent** (10) Patent No.: **US D1,000,459 S**
Ho et al. (45) Date of Patent: ** Oct. 3, 2023

(54) **DISPLAY SCREEN OR PORTION THEREOF WITH A GRAPHICAL USER INTERFACE**

(71) Applicant: **AI Biomaterial Healthtech Ltd.**, Kowloon (HK)

(72) Inventors: **Yen-Yi Ho**, Taoyuan (TW); **Yen-Yun Huang**, Hsinchu (TW); **Huei-Yun Gong**, New Taipei (TW)

(73) Assignee: **AI BIOELECTRONIC HEALTHTECH CO. LTD.**, Taoyuan (TW)

(**) Term: **15 Years**

(21) Appl. No.: **29/812,131**

(22) Filed: **Oct. 19, 2021**

(30) **Foreign Application Priority Data**
